US00D608591S

(12) **United States Design Patent**
Hillebrenner et al.

(10) **Patent No.:** **US D608,591 S**
(45) **Date of Patent:** **** Jan. 26, 2010**

(54) **CUP**

(75) Inventors: **William Hillebrenner**, Chicago, IL (US); **Weston Koennecke**, Oak Park, IL (US)

(73) Assignee: **Solo Cup Operating Corporation**, Lake Forest, IL (US)

(**) Term: **14 Years**

(21) Appl. No.: **29/320,019**

(22) Filed: **Jun. 18, 2008**

(51) LOC (9) Cl. **07-01**

(52) U.S. Cl. **D7/531; D7/509**

(58) **Field of Classification Search** D7/500, D7/509, 396.2, 396.4, 387, 392.1, 523, 624.1, D7/532; D9/744, 516, 549, 551; 215/387, 215/DIG. 7, 382; 220/675, 703, 592.16, 220/592.17; 206/520, 519; D5/7, 99; 428/34.3; 229/400

See application file for complete search history.

(57) **CLAIM**

The ornamental design for a cup, as shown and described.

DESCRIPTION

FIG. 1 is a perspective view showing a first embodiment of our new design of a cup;

FIG. 2 is a front view thereof, the rear view being a mirror image thereof;

FIG. 3 is a top view thereof;

FIG. 4 is a side view thereof, the opposite side being a mirror image thereof;

FIG. 5 is a bottom view thereof;

FIG. 6 is a perspective view showing a second embodiment of our new design of a cup;

FIG. 7 is a front view thereof, the rear view being a mirror image thereof;

FIG. 8 is a top view thereof;

FIG. 9 is a side view thereof, the opposite side being a mirror image thereof; and,

FIG. 10 is a bottom view thereof.

The broken lines represent portions of the structure that are not included in the claim.

1 Claim, 6 Drawing Sheets
